PORTABLE PUNCH

Dale A. Benner, Alton, Ill.

Application November 4, 1939, Serial No. 302,816

7 Claims. (Cl. 164—101)

This invention relates to portable punches of the type specially adapted for use in punching holes through the webs of metallic rails and other metal shapes where high compressive forces are utilized in the operation of the punch.

Objects of the invention are to provide a punch comprising a strong metallic frame constructed and arranged to sustain and resist distortion by the compressive forces to which the punch is subjected when used; to provide a punch of this type having means for supporting removable, replaceable and interchangeable dies in a fixed position in the frame in cooperative relationship with a shaft for operating a punch to form holes through rails and other elements interposed between the punch and any selected die; and to provide a novel form of mechanism for operating the punch shaft.

Another object of the invention is to provide a portable punch of this type having a sleeve attached to its outer end and provided with a circumferential series of teeth or splines, in combination with a frame supported by said sleeve for relative rotation thereon, means for securing the frame on and about the sleeve for independent rotary movements, and a reversible pawl supported by said frame and arranged to engage with the teeth or splines on said sleeve to rotate said sleeve and thereby said shaft when the frame is turned in one direction, and to escape over said teeth or splines when the frame is turned in the opposite direction, means for reversing the position of said pawl whereby turning movements may be imparted to the shaft in either direction, and means in connection with said frame for engaging a bar or lever for actuating said frame to turn said shaft.

Other objects and advantages of the invention will be readily apparent from the following description, reference being made to the annexed drawing, in which—

Fig. 1 is a side elevation of my improved portable punch, the ratchet operating mechanism thereof being omitted.

Fig. 2 is an outer end of side elevation of the ratchet operating mechanism for the punch.

Fig. 3 is a longitudinal sectional view showing the cooperative relationship of the parts of the operating mechanism.

Fig. 4 is a cross-sectional view of the operating mechanism showing the pawl engaging the cooperating sleeve to rotate the latter in one direction.

Fig. 5 is a similar sectional view showing the pawl disengaged from the operating sleeve and

turned to position to engage and rotate the sleeve in the opposite direction.

Fig. 6 is a cross-sectional view on the line 6—6 of Fig. 4.

Fig. 7 is an end elevation showing a different 5 polygonal form on the end of the screw shaft for engaging the ratchet sleeve.

The frame of my improved punch may be of the same light weight and extremely strong construction as that disclosed in my copending application Serial No. 302,815 filed on even date herewith. As disclosed in said application, the metallic frame is generally of C-shape, including a flat portion 1, outer marginal reinforcing flanges 2 terminating at the opposite axially 10 aligned portions 3 and 4, and also provided at its inner margin with opposite curved flanges 5 united at their ends with the portions 3 and 4, and a plurality of outwardly diverging flanges 6 connecting the flanges 2 and 5, as shown. The 20 device is formed with a suitable handle 7. The waste discharge hole 9 communicates with a recess 10 adapted to receive and support interchangeable dies 11 each of which has a bore 12 therethrough. As in my said companion application, this construction permits the interchange and substitution of different dies for different types of work. The shaft 16 is screwed through a threaded hole in the supporting portion 4 for longitudinal movements toward and from the die 30

11. A punch body 18 formed with a circumferential groove 19 is rotatively supported within the inner end of the shaft 16 by pins 21, and is formed with a punch extension 22 on its projecting end. These pins 21 may be removed and replaced to permit the removal and substitution of one punch for another. 35

The outer end of the shaft 16 is formed with a polygonal portion 26. A sleeve 27 is mounted on or attached to the polygonal portion 26 and 40 is formed with a circumferential series of teeth or splines 28. The ends of the sleeve 27 extend beyond the teeth 28. An annular frame 29 has an internal diameter slightly in excess of the diameter of the sleeve 27 including the teeth 28, 45 and has at one end a flange 30 enclosing one projecting end of the sleeve 27 beyond the ends of the teeth 28. A ring 31 is pressed into the opposite end of the frame 29 and is complementary to the flange 30. The distance between the flange 30 and the ring 31 is slightly greater than the length of the teeth 28. The flange 30 and the ring 31 cooperate to hold the frame 29 in assembled connection with the sleeve 27 and to prevent detachment or separation of said parts. 50 55

If desired, one or more set screws 32 may be engaged in threaded holes in the frame 29 and with the ring 31 to cooperate with the pressed fit of said ring to prevent detachment or separation thereof from the frame 29 and to leave said frame 29 freely rotative on and about the sleeve 27. The frame 29 is formed with an integral radial tubular extension 33 in which a ratchet head or pawl 34 is mounted for longitudinal and turning movements.

A tooth 35 is formed integral with the inner end of the head 34, and is provided with one abrupt wall 36 and an oppositely formed inclined wall 37. The head 34 is formed rigid with a stem 38 extending outwardly through a combined bearing and latch block 39 fitted and secured within the outer end of the tubular part 33 by a retaining pin 40. A combined selector and latch device 41 is rigidly attached to the outer end of the stem 38 and is formed with a tooth 42 adapted to engage in notches 43 in the outer end of the part 33 and in the block 39. A spring 44 encircles the stem 38 between the head 34 and the block 39 and functions to press the head 34 in a direction to engage the tooth 35 with the teeth 28.

When there is resistance to rotation of the shaft 16, as when the punch 22 is in contact with the work, the frame 29 may be turned in one direction without turning said shaft 16. This is because the inclined wall 37 of the tooth 35 will slide against and over the teeth 28, the spring 44 yielding to permit necessary movement of the ratchet device. However, when the frame 29 is turned in the opposite direction, the abrupt wall 36 will positively engage the respective teeth 28 and thereby turn the shaft 16.

As may be understood by a comparison of Figs. 4 and 5, the position of the ratchet device may be reversed in order to rotate the shaft 16 in reverse directions. In the adjustment shown in Fig. 4, the shaft 16 will be rotated in a clockwise direction; and, in the adjustment shown in Fig. 5, the shaft will be rotated in a counter-clockwise direction when the ratchet device engages the teeth 28 of the sleeve 27.

A radial socket 45 is formed integral with the frame 29 and preferably adjacent to and integral with the extension 33, and is designed and adapted to receive one end of an operating lever or bar for actuating the operating mechanism to rotate the shaft 16. By oscillation of such an operating lever or bar, the frame 29 may be rocked about the sleeve 27 to impart successive turning movements to said sleeve and thereby to the shaft 16, the ratchet device escaping over the teeth 28 of the sleeve 27 during return or ineffective movement of the parts.

In this device, the operating mechanism may be permanently or detachably secured to the polygonal portion 26 of the shaft 16. Preferably, the operating mechanism is detachable from said shaft in order to facilitate carrying of the device from place to place.

It should be apparent that the invention attains all of its intended objects and purposes very efficiently and satisfactorily, and may be varied within the scope of equivalent limits without departure from the nature and principle of the invention as defined by the appended claims.

I claim:

1. In a portable punch comprising a metallic frame of approximately C-shape having enlarged axially aligned die and punch supporting portions at its ends, and a die attached to said die support-

ing portion; a shaft screwed through said punch supporting portion for movement toward and from said die and having a punch attached to the inner end thereof for cooperation with said die, a ratchet sleeve attached to the outer end of said shaft for rotating the same, an annular frame enclosing and rotative about said ratchet sleeve, a pawl supported by said frame for engaging and turning said sleeve and thereby said shaft in one direction by turning movements of said frame and arranged to escape about and leave said sleeve stationary when said frame is turned in the opposite direction, a device for moving said pawl to reverse position to turn said sleeve and thereby said shaft in the opposite direction, and means rigid with said frame for engaging a lever bar for operating said frame to rotate said shaft.

2. In a portable punch comprising a metallic frame having enlarged axially aligned die and punch supporting portions at its ends, and a die attached to said die supporting portion; a shaft screwed through said punch supporting portion for movement toward and from said die and having a punch attached to the inner end thereof for cooperation with said die, a sleeve attached to the outer end of said shaft, a circumferential series of teeth integral with said sleeve, an annular frame enclosing and wholly supported by said sleeve, means in connection with said frame cooperating with said teeth to prevent displacement of said frame relative to said sleeve, a pawl supported by said frame for engaging and turning said sleeve in one direction by turning movements of said frame in said direction and arranged to escape about and leave said sleeve stationary when said frame is turned in the opposite direction, a spring for engaging said pawl with said teeth on said sleeve, and means for manually turning said pawl to and latching said pawl in different adjusted positions for operation to turn said sleeve in either direction as desired.

3. In a portable punch comprising a metallic frame having enlarged axially aligned die and punch supporting portions at its ends, and a die attached to said die supporting portion; a shaft screwed through said punch supporting portion and having a punch attached to the inner end thereof for cooperation with said die, a sleeve attached to the outer end of said shaft for rotating the same, a series of circumferential ratchet teeth integral with said sleeve, a frame enclosing and rotative about said sleeve, means rigid with said frame engaging the ends of said teeth and holding said frame about said sleeve, a tubular radial extension integral with said frame, a pawl mounted in said extension for engaging and turning said sleeve in one direction by turning movements of said frame in one direction and leaving said sleeve stationary when said frame is turned in the opposite direction, a spring for actuating said pawl into engagement with said sleeve, and a manually adjustable latch device for holding said pawl in adjusted position to turn said sleeve in either direction as desired by operation of said frame.

4. In a portable punch comprising a metallic frame having enlarged axially aligned die and punch supporting portions at its ends, and a die attached to said die supporting portion; a shaft screwed through said punch supporting portion and having a punch attached to the inner end thereof for cooperation with said die, a sleeve attached to the outer end of said shaft, a circumferential series of ratchet teeth integral with said sleeve, an annular frame enclosing and rotative

about said sleeve, a flange integral with said frame engaging one end of said ratchet teeth, a ring secured within the opposite end of said frame engaging the opposite end of said teeth from said flange, a tube integral with said frame pawl mechanism supported in said tube for engaging and turning said sleeve in either direction as desired, and a socket integral with said frame and disaligned from said tube for engagement with an operating lever.

5. In a portable punch comprising a metallic frame having enlarged axially alined die and punch supporting portions at its ends, and a die attached to said die supporting portion; a shaft screwed through said punch supporting portion for operating a punch toward and from said die, a ratchet sleeve attached to the outer end of said shaft, a frame wholly supported by and rotative about said sleeve, a radial tube integral with said 10 frame having a plug mounted in its outer end, a pawl device mounted for sliding and turning movements in said tube for engaging and turning said ratchet sleeve and thereby said shaft in either direction as desired, a spring enclosed in said tube between said pawl device and said plug, a stem attached to said pawl device and extending through said plug for longitudinal and turning movements, and a latch member attached to the outer end of said stem for engaging said plug to hold said pawl device in position to turn said ratchet sleeve in either direction as desired.

6. In a portable punch comprising a metallic frame having enlarged axially alined die and punch supporting portions at its ends, and a die attached to said die supporting portion; a shaft screwed through said punch supporting portion for operating a punch toward and from said die, a ratchet sleeve attached to the outer end of said shaft, a frame wholly supported by and rotative about said sleeve, a radial tube integral 15

with said frame having a plug mounted in its outer end, a pawl device mounted for sliding and turning movements in said tube for engaging and turning said ratchet sleeve and thereby said shaft in either direction as desired, a spring enclosed in said tube between said pawl device and said plug, a stem attached to said pawl device and extending through said plug for longitudinal and turning movements, a combined handle and latch member attached to said stem for manual adjustment of said pawl device in positions for engagement with said plug to hold said pawl device in position to turn said ratchet sleeve in either direction as desired, and a socket integral with said frame arranged to engage a lever for operating said frame.

7. In a portable punch comprising a metallic frame having enlarged axially alined die and punch supporting portions at its ends, and a die attached to said die supporting portion; a shaft screwed through said punch supporting portion and having a punch for cooperating with said die, a ratchet sleeve attached to the outer end of said shaft for rotating the same, an annular frame mounted on and rotative about said ratchet sleeve, a tube extending radially from said frame, a pawl device mounted in said tube for longitudinal movements and for turning movements to different adjusted positions, a tooth in connection with said pawl device for engaging and turning said ratchet sleeve in either direction as desired according to the adjustment of said pawl device, means for latching said pawl device in position to turn said ratchet sleeve in either direction as desired and leaving said pawl device free for longitudinal movements in said tube, and a socket rigid with said frame for engaging a lever to operate said frame.
